UNITED STATES PATENT OFFICE.

ERNEST FLORY, OF LOWELL, MASSACHUSETTS, ASSIGNOR TO UNITED STATES CARTRIDGE CO., OF LOWELL, MASSACHUSETTS, A CORPORATION OF MASSACHUSETTS.

RADIATOR AND METHOD OF MAKING SAME.

Application filed November 20, 1923. Serial No. 602,253.

To all whom it may concern:

Be it known that I, ERNEST FLORY, a citizen of the United States of America, and resident of Lowell, in the county of Middlesex and State of Massachusetts, have invented new and useful Improvements in Radiators and Methods of Making Same, of which the following is a specification.

This invention relates to heat radiators of the type comprising a plurality of tubes mounted together in unitary assemblage with fluid spaces therebetween and more particularly to an improved method and means for confining the fluid space at the sides of the radiator, the top and bottom of the radiator ordinarily being covered by fluid chambers.

In building up radiators of the tubular type for automobiles and other uses it is customary to expand the heads of the tubes into hexagonal or other polygonal form so that when the tubes are assembled together the heads interfit in close relationship but the tubes themselves are spaced from each other. After the tubes are assembled in this relation the assemblage is clamped together and the ends of the tubes are dipped into hot solder for the purpose of integrally uniting the expanded ends.

The means for confining the spaces between the tubes at the sides of the radiator usually comprises sheets of metal soldered to the outer rows of tubes at the sides of the assemblage. With the side walls thus associated with the tubes it has been difficult tightly to secure the side walls so that no leaks occur between the walls and the outer rows of tubes, and after the structure has been completed the walls have a tendency to loosen from the tubular assemblage when subject to vibration or impact.

The objects of the present invention are to associate the side walls with the assemblage of tubes so that a firm joint connection can be readily secured and so that the side walls are protected from injury after the radiator core has been completed.

The invention consists in means for pressing the side walls tightly against the polygonal ends of the radiator tubes while the side walls are being soldered or otherwise secured to the tubes, said means being fastened to the outer sides of the side walls to protect the walls after the tube assemblage has been completed. When the tubes

are assembled with their polygonal ends interfitting the exposed sides of the ends present a zig-zag outline at the side of the assemblage. The side wall which is to be soldered or otherwise attached to said exposed sides of the ends is shaped to have a similar outline so as to interfit with the ends. The aforesaid means for pressing the side wall against the tube ends also has a similar outline adapted to interfit with the outside of the wall, said means preferably comprising interfitting tubes having polygonal ends substantially identical with the end of the radiator tubes. The parts are clamped together in interfitting relationship and the side wall is soldered to the ends of the radiator tubes. The side wall is also preferably secured to the tubes or other pressure means, outside the wall so that the latter are incorporated as an integral part of the radiator.

In order to illustrate the nature of the invention certain concrete embodiments have been shown in the accompanying drawings, in which—

Fig. 1 is an end view of a rectangular radiator core, a portion being broken away;

Fig. 2 is a similar view of a tapered core such as used in certain automobiles;

Fig. 3 is a view similar to Fig. 1, showing the mechanism for clamping the parts together; and

Fig. 4 is a section on line 4—4 of Fig. 3, further illustrating the construction of the clamping mechanism and indicating the step of dipping the ends of the assembled tubes in the hot solder.

The particular embodiment of the invention shown in Fig. 1 comprises a plurality of tubes 1 having hexagonal ends assembled together in interfitting relationship and side walls 2 between the outermost rows of tubes at each side of the radiator. While the side walls 2 may be set in any desired distance from the sides of the core they are preferably set in only one row removed from the sides. These side walls are preferably formed of sheet copper and are correlated to fit between the hexagonal ends of the tubes.

In applying the invention to a tapered core such as shown in Fig. 2 the side walls 2' may be shaped as shown in Fig. 1 and be disposed in a vertical body as shown at the left of Fig. 2 or they may be shaped irregu-

larly to fit between the outermost rows of tubes as shown at the right of Fig. 2, the essential condition being that the side walls are completely covered on the outside with 5 radiator tubes.

The means for clamping the assemblage of tubes together shown in Fig. 3 comprises a rectangular frame 3 and pressure bars 4, 5, 6 and 7 mounted in the frame by means of 10 adjustable screws 8, the bars being forced inwardly by threading the nuts 9 outwardly against the outer frame and being held in position by lock nuts 10 on the outside of the frame 3. The bars 5 and 7 are provided 15 with slots 11 to receive the tenons 12 at the ends of the bars 4 and 6 so that all four bars may lie in the same plane at the same time and be moved inwardly and outwardly independently of each other.

As indicated in Fig. 4 the bars 4, 5, 6 and 20 7 engage the tubes only throughout the central portions of the tubes leaving the ends of the tubes projecting between the frame. After the tubes are securely clamped into 25 position with the side walls 2 pressed into intimate contact both with the tubes inside the walls and also with the tubes outside thereof, the ends of the tubes and side walls are dipped into hot solder as indicated in 30 Fig. 4, thereby integrally to join the expanded ends of the tubes together and to the opposite sides of the side walls 2.

In making a tapered core such as shown in Fig. 2 it has been customary to flatten the 35 outermost rows of tubes at the sides of the core in order to make a relatively flat surface to which to secure the side walls. Obviously this has involved difficulties in securing a tight connection between the side 40 walls and the flattened tubes. According to the present invention the irregular rows of tubes at the sides of the core need not be flattened before the side walls are attached, thereby obviating the difficulty of securing a 45 tight joint as a result of flattening the tubes. However, it will be understood that after the side walls are securely united to the tubes as illustrated in Fig. 2 the irregular contour of the sides of the core may be converted into 50 approximately straight sides by flattening the tubes outside of the side walls; and inasmuch as these are dummy tubes there is no danger of leaks resulting from this flattening.

From the foregoing description it will be 55 evident that the side walls are brought into more intimate contact with the tubes inside thereof by virtue of the interfitting tubes outside of the walls pressing inwardly thereagainst throughout their extent from the top to the bottom of the core. It will also be seen that the side walls are supported more substantially and permanently inasmuch as they are united with tubes on the outside as 60 well as the inside. Moreover the dummy 65

tubes outside the side walls serve as buffers to protect the side walls from injury in assembling the cores and in the use of the radiators into which they are incorporated.

I claim:

1. A radiator comprising an assemblage of tubes having polygonal ends interfitting together, the interfitting ends presenting a zig-zag outline at the side of the assemblage, a side wall having a similar outline fitting against said ends at the side of the assemblage, and means outside said wall having a similar outline interfitting with the wall. 70

2. A radiator comprising a plurality of tubes mounted together in predetermined relationship to form a unitary assemblage with fluid space therebetween, means for confining said space including a wall extending along one side of said assemblage, and other tubes mounted outside said wall 80 in substantially the same relationship to each other and to the tubes inside the wall.

3. A radiator comprising a plurality of tubes mounted together in predetermined relationship to form a unitary assemblage 90 with fluid space therebetween, means for confining said space including a wall extending along one side of said assemblage, and other tubes mounted outside said wall in substantially the same relationship to 95 each other and to the tubes inside the wall, the outside tubes covering substantially the entire outer surface of said wall.

4. A radiator comprising a plurality of tubes mounted together in predetermined 100 relationship to form a unitary assemblage with fluid space therebetween, means for confining said space including a wall extending along one side of said assemblage, and a single row of tubes mounted outside 105 said wall in substantially the same relationship to each other and to the tubes inside the wall.

5. A radiator comprising an assemblage 110 of tubes of the type having expanded polygonal ends interfitting together to form a fluid space between the tubes, and means for confining said space including a wall extending between the tubes near one side of the radiator and interfitting between the heads of juxtaposed tubes at the ends of the 115 radiator.

6. A radiator comprising an assemblage 120 of tubes of the type having expanded hexagonal ends interfitting together to form a fluid space between the tubes, and means for confining said space including a wall extending between the tubes near one side of the radiator, said wall being crimped to interfit with the hexagonal heads of the 125 tubes on each side thereof.

7. The method of making a radiator of a plurality of tubes having polygonal ends which comprises assembling the tubes with the polygonal ends interfitting together and 130

- presenting a zig-zag outline at the side of the assemblage, fitting a side wall having a similar outline against said ends at the side of the assemblage, fitting pressure means 5 having a similar outline, against the outer side of said wall, clamping the parts together, and integrally uniting said wall with the interfitting ends of the juxtaposed tubes while the parts are clamped together.
10. 8. The method of making a radiator to a plurality of tubes having polygonal ends which comprises assembling the tubes with the polygonal ends interfitting together and presenting a zig-zag outline at the side of the assemblage, fitting a side wall having a similar outline against said ends at the side of the assemblage, fitting pressure means having a similar outline, against the outer side of said wall, clamping the parts together, and integrally uniting said wall with the interfitting ends of the juxtaposed tubes and also with the pressure means while the parts are clamped together, whereby the pressure means is incorporated as an integral part of the radiator.
15. 9. The method of making a radiator of a plurality of tubes having expanded polygonal ends which comprises assembling the tubes with their polygonal heads interfitting with each other and with a wall interfitting between the heads of juxtaposed tubes, clamping the parts in this relationship with the heads of the tubes adjacent the wall pressing against both sides thereof, and integrally uniting the hexagonal heads to each other and to opposite sides of the wall while the parts are so clamped.
20. 10. The method of making a radiator of a plurality of tubes having expanded polygonal ends which comprises assembling the tubes with their polygonal heads interfitting with each other and with a wall interfitting between the heads of juxtaposed rows of the tubes, clamping the parts in this relationship with the heads of the tubes adjacent the wall pressing against both sides thereof, and dipping the ends of the tubes and wall into molten solder while so clamped.

Signed by me at Lowell, Massachusetts, 50
this eighth day of November 1922.

ERNEST FLORY.
